TIEBACK CURTAIN

Philip A. Burrage, Weymouth, Mass., assignor to
 Robertson Factories, Inc., New York, N. Y., a
 corporation of Connecticut

Application October 21, 1947, Serial No. 781,131

13 Claims. (Cl. 160—349)

1

This invention relates to improvements in window curtains of the tie-back variety. More particularly it provides a tie-back curtain section whose tie-back element may be variously attached to or associated with the curtain section to attain a variety of draped effects.

It is among the objects of the invention to provide a tie-back curtain section having a tie-back extending around the outer edge region of the curtain section and thence inward on opposite sides of the curtain section, with the ends of the tie-back engaging the curtain section at an inner edge region thereof.

Another object is to provide a tie-back curtain section having a tie-back extending around the outer edge region of the curtain section and thence inward on opposite sides of the curtain section, with one or both ends of the tie-back adjustably engaging the curtain section at an inner edge region thereof.

A further object is to provide a tie-back curtain section having a tie-back with its ends at opposite sides of the curtain section and adjustably secured to the curtain section whereby one or both ends of the tie-back may be selectively secured to the curtain at different locations thereon to attain different draped effects.

Yet another object is to provide a panel and tie-back curtain section in which the central portion of the tie-back engages loosely around the outer edge region of the panel and the opposite ends of the tie-back are detachably secured to the curtain section at the inner edge region of the panel.

Still another object of the invention is to provide a panel and tie-back curtain section in which the tie-back has one of its ends secured to the curtain section in the region of the inner edge of the panel and extends thence in relatively slidable frictional engagement with one side of the panel to a location adjacent to the outer edge of the panel where it reverses its direction and extends generally in direction toward the inner edge region of the panel and is detachably secured substantially inward of the outer edge of the panel.

Another object is to provide a curtain tie-back device having resilient means removably and adjustably engageable with a curtain by a resilient clamping of the curtain at a selected location thereon and having generally oppositely disposed portions for extending on opposite sides of the curtain from the said clamping location thereon toward an edge region of the curtain.

Still another object is to provide a curtain tie-

2

back device made of resilient relatively stiff material having generally U-shape for extending around one edge region and along opposite sides of the curtain, one arm of the U having sinuous extent providing spaced grooves facing the other arm, within which grooves the curtain may be arranged to attain a predetermined pleated drape effect.

It is, moreover, my purpose and object generally to improve the structure and effect of tie-back window curtains.

In the accompanying drawings:

Fig. 1 is a front elevation of a mounted and draped tie-back curtain section embodying features of my present invention;

Fig. 2 is a somewhat diagrammatic cross-sectional view on line 2—2 of Fig. 1, on a larger scale, and showing the tie-back in dotted lines detached from the curtain section;

Fig. 3 is a fragmentary cross-sectional view showing a modified form of detachable connection for at least one end of the tie-back;

Fig. 4 is a fragmentary cross-sectional view showing the tie-back extending around the ruffle at the inner edge of the curtain section with the ends of the tie-back detachably secured together;

Fig. 5 is a front elevation of a portion of a curtain section having a tie-back casing secured thereon and having one end of a tie-back secured to the curtain inward beyond the inner end of the casing, with the tie-back extending thence outward and slidably through the casing and then back inward for detachable securement of its second end, with a ruffled portion of the tie-back in covering relation to the casing;

Fig. 6 is a view generally similar to Fig. 2, but showing a modified form of tie-back device;

Fig. 7 is a side elevation, with one end slightly in perspective, of the resilient tie-back device of Fig. 6, with its fabric covering portion removed;

Fig. 8 is a front face view of the fabric covering portion of the tie-back device of Figs. 6 and 7; and

Fig. 9 is a view generally similar to Fig. 7, but illustrating a modified form of resilient device which provides multiple clamping of pleats of a curtain.

Referring to the drawings, the curtain section as shown in Fig. 1 should be considered as merely representative of window curtain sections generally, made of textile fabric or other suitable sheet material. As herein illustrated, the curtain section comprises a panel 10 with a relatively wide ruffle 12 extending along the in-

ner and top edges of the panel. The bottom edge (not shown) may be similarly bordered by a ruffle. The outer edge is hemmed as at 14 and is shown without a ruffle although, obviously, it too may have a ruffle therealong, if desired.

According to the invention, the curtain section is gathered and draped, to provide desired aesthetic and utilitarian effects, by means of a tie-back member 16 or 17 whose opposite ends are secured to the curtain section in the region of the inner ruffled edge of panel 10 and which has extent between its ends from said inner edge region of the panel to the outer edge thereof where it reverses its course and extends back inward to the inner edge region of the panel.

In one form, shown in Fig. 2, the tie-back member 16 extends outward from one of its end-securements, passes around the outer edge of panel 10 and extends thence inward to its other end-securement. As represented, in Fig. 2, both ends of the tie-back are detachably secured to the curtain section at the juncture of the ruffle 12 with the inner edge portion of panel 10. The securing may be by any suitable means, such as the headed pin 18 thrust through one end of the tie-back and through the curtain section, and through the other end of the tie-back. The tip end portion of the pin may be bent over against the adjacent end portion of the tie-back, as suggested in Fig. 3, or an element 20, of rubber or the like, may be pressed over the tip end of the pin as shown in Fig. 2. The element 20 frictionally grips the pin and may constitute one jaw of a clamp whose other jaw is the head of the pin. The clamping action thus attained avoids a mere holding by pin-engagement with the more or less fragile sheet material.

It will be obvious that the tie-back ends, in the Fig. 2 form, may be selectively located and secured at any desired point along the inner edge region of the panel 10, or one end may be secured at one point and the other end at another point, as indicated in Fig. 1.

In the Fig. 3 form, the end 16' of tie-back 16 is shown stitched to the curtain section, in which case only the end 16'' is adjustably and detachably secured to the curtain section by pin 18 or other securing means while Fig. 4 shows the tie-back extending around both the outer edge and the inner ruffled edge of the curtain section, with the ends of the tie-back detachably secured together adjacent to the inner edge.

The Fig. 5 modification has a flexible strip 22 stitched to the panel 10 to provide a generally tubular open-ended casing on the panel extending from a location adjacent to the inner edge of the panel 10 to a location adjacent to the outer edge thereof. A portion 24 of a tie-back extends slidably through the casing, with its inner end secured at 23 to the curtain section and with its outer end joined to the wider portion 26 of the tie-back, which latter is adapted to be laid over in covering relation to the casing 22, and to have its inner end detachably secured to the curtain section, or to the casing 22, adjacent to the inner edge of panel 10 as by the pin 18. The securing of the tie-back at 23 may be either a fixed or a detachable securement.

It is a feature of the invention, that a panel and tie-back curtain section embodying my improved features provides a more effective gathering of the panel and maintenance thereof in any particular draped condition, as compared

with all prior proposals of which I am aware. For example, in the Figs. 1-4 forms, the panel is effectively drawn and gathered toward the restraining portion of the tie-back which extends around the outer edge 14 of the panel 10, so that there is a definite obstruction against which the gathering proceeds, with the inwardly extending portions of the tie-back, at opposite sides of the panel, constituting lateral abutments frictionally engaging the crests of the gathers and restraining relative movement of the gathers and the tie-back after a particular draped arrangement has been attained. In other words, the panel becomes definitely confined within the tie-back, as compared with prior tie-back curtain proposals where the tie-back provides no definite limiting obstruction to outward movement of the outer edge of the curtain section or panel.

In the Fig. 5 form, the casing 22 and tie-back portion 24 provides restraining friction when the panel 10 and the casing become gathered, and here again the return bend of the tie-back restrains outward movement of the outer edge 14 when the tie-back is fastened.

In the Figs. 1-5 forms, the tie-back element is of flexible material such as fabric, or the like. The embodiments of the invention illustrated in Figs. 6-9 employ tie-back devices made of wire or other suitable material which, preferably, are resilient, or have resilient portions, for resilient engagement of a curtain. As represented in Figs. 6 and 7, the tie-back device 11 is formed of wire bent into the shape as best seen in Fig. 7, with ring portions 28 at the opposite ends of the wire resiliently urged together to provide an end-clamp on the tie-back device. From one of the ring portions 28, the wire has generally straight extent, as at 30, to a U-bend 32 at the opposite end of the device whence the wire has sinuous extent at 34 back to the other ring portion 28. This device may be arranged on a curtain by spreading apart the ring portions 28 and passing one of the vertical edges of a curtain between the rings and between the portions 30, 34 until the entire panel portion of the curtain is within the device. As represented in Fig. 6, the device has been applied by having the outer edge of the curtain inserted first between ring portions 28, so that this outer edge is adjacent to the U-bend 32. The ring portions 28 are shown in Fig. 6 in clamping engagement with the hem region 36 at which the inner edge ruffle 12 of the curtain is secured, so that the tie-back device does not extend around ruffle 12. Obviously, if desired, ruffle 12 may be arranged within the device, in which case the ring portions 28 would engage each other beyond the ruffle.

The ring portions 28 may resiliently clamp the curtain with sufficient pressure to grip and hold the clamped portion of the curtain in a manner to retain the tie-back device in a selected position on the curtain, with friction of the device against the gathered curtain within the device restraining relative slippage due to the weight of the device. Preferably, however, the outer end of the tie-back device will be equipped with fastening means 38 by which the device may be removably attached to a hook, or the like, at a convenient location on the window casing.

If the resilient clamping at the ring portions 28 should prove inadequate for any reason, the ring portions may be mechanically secured together through the curtain by securing means

comparable to the securing means 18, 20 of Fig. 2, and shown dotted in Fig. 6.

It is a feature of the Figs. 6 and 7 form that the sinuous portion 34 of the device provides a series of grooves in which gathered portions of the curtain may be uniformly seated to attain a predetermined gathered draping of the curtain. It will be obvious that the gathers may be readily formed with general uniformity within the tie-back device, and the relatively long sinuous surface areas of engagement of the device with the curtain material tends to maintain the predetermined gathered effect more adequately and more attractively than can be accomplished with prior tie-back devices. The relatively straight portion 30 of the device which extends at the front of the curtain conveniently may be covered by a strip of fabric or the like which may be removably slipped over the portion 30. Such a fabric cover is shown at 40 in Figs. 6 and 8, it being represented as an attractively ruffled strip on whose rear face is stitched a narrower strip 42 which provides a longitudinal flat tube or pocket open at its opposite ends so that the composite strip 40, 42 may be slipped over the portion 30 of the tie-back device to decoratively cover the wire device.

As with the tie-backs of Figs. 1-5, the Figs. 6-8 form may be selectively positioned at any desired location along the curtain.

The Fig. 9 modification is generally similar to the Fig. 7 form but the sinuous bends are shaped as at 44 to resiliently pinch or grip the respective gathers of a curtain.

Obviously, various means may be provided on the tie-back devices of Figs. 6, 7 and 9 for mechanically securing the ends of the wires to a curtain, such as forming the ends of the wire with a safety-pin-type of fastening, with one end of the wire adapted to pass through the curtain.

I claim as my invention:

1. A window curtain section comprising a panel of flexible sheet material having inner and outer edges, a unitary tie-back member extending integrally around the outer edge of the panel and thence inward at opposite sides of the panel with its opposite ends disposed adjacent to the inner edge portion of the panel, means at that region of the tie-back member which extends around the outer edge of the panel for removably attaching the tie-back member to a window casing, and clamping means at the inner end portions of the tie-back member for adjustably clamping said end portions of the tie-back member and an inner edge marginal portion of said panel together selectively at any of different locations along the inner edge margin of the panel.

2. A window curtain section comprising a panel of flexible sheet material having inner and outer edges, and having a ruffle extending along at least the inner edge of the panel, a tie-back member having one end attached to the curtain section in the region of the inner edge of the panel and spaced from the free edge of said ruffle, and extending thence outwardly at least to the outer edge of the panel where it reverses its direction and extends inward generally toward the inner edge of the panel, means at the outer portion of the tie-back member for removably attaching the tie-back member to a window casing, and clamping means having coacting portions at opposite sides of said panel for adjustably clamping the second end of the tie-back member and a portion of the curtain section together selectively at any of various locations along the inner edge margin of the panel.

tions between the top and bottom of the panel.

3. A window curtain section comprising a panel of flexible sheet material having inner and outer edges, a tie-back member extending around the outer edge of the panel and inward on opposite sides of the panel, with an end of the tie-back member at each side of the panel, and clamping means at said ends of the tie-back member adjustably clamping a portion of said panel between the ends of the tie-back member selectively at any of various locations along the inner edge region of the curtain section.

4. A window curtain section comprising a panel of flexible sheet material having inner and outer edges, a tie-back member associated with the panel in generally U-shape with the bridge of the U loosely engaged around the outer edge of the panel and with the arms of the U extending inward on opposite sides of the panel, means at the bridge portion of the U-shaped tie-back member for removably suspending the tie-back on a window casing, and clamping means at the ends of the U-arms of the tie-back member for adjustably clamping a portion of said panel between the ends of the tie-back member selectively at any of various locations along the inner edge region of the panel, thereby to effect a draping of the curtain section with a gathering of the panel material toward the bridge of the U and into frictional engagement with the arms of the U.

5. A window curtain section comprising a panel of flexible sheet material having inner and outer edges, a tie-back member associated with the panel in generally U-shape with the bridge of the U loosely engaged around the outer edge of the panel and with the arms of the U extending inward on opposite sides of the panel, means at the bridge portion of the U-shaped tie-back member for removably suspending the tie-back on a window casing, and means securing the ends of the U-arms of the tie-back to the curtain section at the inner edge region of the panel, the said securing means for the end of at least one of the U-arms being an adjustable clamp for clamping the end of said one of the U-arms and an inner edge portion of said panel together selectively at any of various locations along said inner edge region of the panel.

6. A window curtain section comprising a panel of flexible sheet material having inner and outer edges, a tie-back device extending around one of said edges and thence generally transversely of the panel on opposite sides thereof with an end of the tie-back device disposed on each side of the panel adjacent to the opposite edge region of the panel, and means at said ends of the tie-back device in adjustable clamping engagement with the panel at said opposite edge region thereof, said means being adjustable along said panel for clamping the panel at any of various locations along said opposite edge region thereof.

7. A window curtain section comprising a panel of flexible sheet material having inner and outer edges, a tie-back device of relatively stiff resilient material extending around the outer edge of the panel and inward on opposite sides of the panel, with an end of the tie-back device disposed on each side of the panel adjacent to an inner edge region of the panel, said ends of the tie-back device being in resilient clamping engagement with said inner edge region of the panel and selectively adjustable for clamping the

panel at any of various locations along said inner edge region of the panel.

8. A window curtain section comprising a panel of flexible sheet material having inner and outer edges, a tie-back device of relatively stiff resilient material extending around said outer edge of the panel and thence generally transversely of the panel on opposite sides thereof, with end portions of the tie-back device disposed adjacent to the inner edge region of the panel 10 and coacting to provide a resilient clamp for adjustably clamping an inner edge portion of the panel selectively at any of various locations along said inner edge region of the panel, and preformed sinuous means at one of said transversely extending portions of the tie-back device for sinuously engaging gathered portions of the panel within the tie-back device, thereby to effect a general uniformity of gathering of the panel in the process of draping of the panel.

9. A window curtain section comprising a panel of flexible sheet material having inner and outer edges, a tie-back device comprising a resilient frame having a portion extending around the outer edge of the panel and portions extending thence inward on opposite sides of the panel to locations adjacent to the inner edge of the panel, clamping means on said frame clamping an inner edge portion of the panel between adjacent inner portions of said frame and selectively adjustable for effecting the said clamping at any of various locations along said inner edge of the panel, and means on said frame at a said inwardly extending portion thereof for effecting a predetermined gathering of the panel material within the frame.

10. A window curtain section comprising a panel of flexible sheet material having inner and outer edges, a tie-back device comprising a resilient frame having a portion extending around the outer edge of the panel and portions extending thence inward at the rear side and front side of the panel, clamping means clamping an inner edge portion of said panel between inner portions of said frame and selectively adjustable for effecting the said clamping at any of various locations along said inner edge of the panel, a cover member removably arranged on said portion of the frame which extends inwardly at the front side of the panel, and panel gathering means distributed along said portion of the frame which extends inwardly at the rear side of the panel.

11. A window curtain section comprising a panel of flexible sheet material having inner and outer edges, a tie-back device having two relatively stiff resilient arms disposed on opposite sides of the panel and having means connecting the arms together adjacent to the outer edge of

the panel, said connecting means permitting relative movement of the arms into and out of panel-engaging relation with the inner ends of the arms selectively at any of various locations along the inner edge of the panel, and said arms, when in their said panel-engaging relation, having portions resiliently clamping an inner edge portion of the panel at a selected location therealong.

12. A tie-back device for a curtain section, comprising two relatively stiff resilient arms connected together at one end of the device and relatively movable into and out of relative positions for resiliently clamping and releasing a curtain section, said device being adapted to engage a curtain section with the said arms on opposite sides of the section and with said end-connection of arms adjacent to the outer edge of the section and with the inner ends of said arms selectively at any different locations along the section, a covering member mounted on the arm which extends at the front side of the curtain section, and means on said covering member, at the region of the outer edge of the curtain section, for detachably connecting said member and device to a window casing.

13. A window curtain section comprising a panel of flexible sheet material having inner and outer edges, a tie-back member having one end engaging the panel in the region of the inner edge of the panel and having a portion extending thence outwardly at least to the outer edge of the panel and then reversing its direction to provide an integral portion extending inward generally toward the inner edge of the panel, and clamping means adjustable along the inner marginal portion of the panel adapted to clamp at least one of the ends of the tie-back member to the said panel selectively at any of a variety of locations along the inner marginal portion of the panel and in spaced relation to the inner edge of the panel.
